CLAIM

The ornamental design for a carafe with steeping filter support, as shown and described.

DESCRIPTION

FIG. 1 is a top isometric view of a first embodiment of a carafe with steeping filter support showing our new design; FIG. 2 is a top plan view thereof;

FIG. 3 is a bottom plan view thereof;

FIG. 4 is a front side elevation view thereof, a back side elevation view being identical;

FIG. 5 is a left side elevation view thereof, a right side elevation view being identical;

FIG. 6 is a top isometric view of a second embodiment of a carafe with steeping filter support showing our new design; FIG. 7 is a top plan view thereof;

FIG. 8 is a bottom plan view thereof;

FIG. 9 is a front side elevation view thereof, a back side elevation view being identical;

FIG. 10 is a left side elevation view thereof;

FIG. 11 is a right side elevation view thereof;

FIG. 12 is a top isometric view of a third embodiment of a carafe with steeping filter support showing our new design; FIG. 13 is a top plan view thereof;

FIG. 14 is a bottom plan view thereof;

FIG. 15 is a front side elevation view thereof, a back side elevation view being identical;

FIG. 16 is a left side elevation view thereof; and,

FIG. 17 is a right side elevation view thereof.

The broken lines showing portions of the carafe with steeping filter support are for the purpose of illustrating environmental structure only and forms no part of the claimed
